(57) CLAIM

The ornamental design for a stand for a comestible maker, as shown and described.

DESCRIPTION

FIG. 1 is a perspective view of a stand for a comestible maker showing a first embodiment of our new design;

FIG. 2 is a top plan view thereof;

FIG. 3 is a rear elevational view thereof;

FIG. 4 is a front elevational view thereof;

FIG. 5 is a left side elevational view thereof, the right side elevational view being a mirror image of FIG. 5; and,

FIG. 6 is a bottom plan view thereof.
